MACHINE FOR TRANSFER PRINTING ONTO
CURVED SURFACES

Vincent J. Tenety, Jersey City, N. J.; Helen M. Tenety executrix of said Vincent J. Tenety, deceased

Application May 6, 1947, Serial No. 746,358

11 Claims. (Cl. 101—36)

1
The present invention relates to a new improved machine for transfer printing onto curved surfaces, especially of containers and the like.

Although it is known to print onto plane surfaces of rectangular containers, for instance, by aligning such plane surfaces on the bed of a conventional flat-bed proof press, of the type known in the paper printing art, with an impression plate, and thereupon transferring the design onto said plane surface by means of an offset blanket roller traveling on the longitudinal tracks of said proof press, this economical and simple method is not possible of application where curved surfaces are to be printed. This drawback has now been eliminated by the machine of my invention, wherein mechanical means are provided which compels a transfer roller into releasably engageable printing contact with a rotated blade supported curved surface and rotates said roller, while maintained in such contact, through an angle sufficient to contact all of the design carried by said roller with said surface.

The application of my machine is by no means limited to printing on cylindrical or symmetrically curved surfaces, my machine being especially well suited for pressure printing onto irregularly curved surfaces. Among its other advantages are its capability of simultaneously printing multi-color impressions onto a plurality of curved surfaces, the exactness of registration of the printed impression possible with respect to any protuberance, such as a handle or the like, on the curved surface to be printed, its simplicity of design and operation and its economy of manufacture, and the fact that the impression borne by the transfer roller may be obtained from flat rather than curved impression plates. Further advantages and characteristics of my invention will appear from the following description read in conjunction with the drawing, in which:

Fig. 1 is a left side view of one embodiment of the machine of my invention with certain parts removed;

Fig. 2 is a left side view of the embodiment of Fig. 1 shown in printing position with certain parts removed;

Fig. 3 is a plan view of the showing of Fig. 1 with certain parts removed;

Fig. 4 is a front view of the showing of Fig. 2 with certain parts removed;

Fig. 5 is a front view of the showing of Fig. 1 with certain parts removed;

Fig. 6 shows a detail of part of the construction shown in Figs. 1 to 5;

2

Fig. 7 shows a detail of another part of the construction shown in Figs. 1 to 5;

Fig. 8 is a side view of the showing of Fig. 7, in printing position;

Fig. 9 is a partial left side view of another embodiment of the machine of my invention;

Fig. 10 is a front view of the showing of Fig. 9 with certain parts removed;

Fig. 11 is a sectional elevation corresponding to plane 11—11 of Fig. 9 but showing the machine in printing position;

Fig. 12 is a sectional elevation along the plane 12—12 of Fig. 10;

Fig. 13 is an enlarged side view, with certain parts removed, of part of the showing of Fig. 11;

Fig. 14 is a sectional view along plane 14—14 of Fig. 13;

Fig. 15 is a detail of part of the construction shown in Figs. 9 to 14;

Fig. 16 shows a detail of part of the construction shown in Figs. 1 to 12, and

Fig. 17 is a cross-section along the plane 17—17 of Fig. 16.

Referring to the drawing (Figs. 1 to 12), the framework of the machine consists of angle-iron legs 1, 2, 3 and 4 held together by cross members 5—14 inc. Impression plates 15 and 16 (Figs. 3, 4, 5, 10 and 11) shown for the purpose of illustration in duplicate in the drawing and comprising together the design to be printed, are secured to beds 17 and 18 respectively by clamping members 19, 20, 21, 22, respectively (Fig. 3). These beds are so located within the framework of the machine that inked impression plates 15 and 16 transfer their ink impressions, registered, onto transfer roller 25 (see especially Figs. 3, 6 and 10) which travels over racks 27 and 28 (secured to the outside of longitudinal cross members 5 and 8 respectively) via pinions 30 and 31 splined onto the ends of shaft 32 of roller 25. As shown in Fig. 6 but omitted from the other figures, handle 26 may be provided on the end of shaft 32 to facilitate its movement. Beds 17 and 18 (Figs. 1, 2, 3, 5 and 11) are secured in this position, for instance by pairs of straps 33 and 34 respectively holding angles 35 and 36 respectively, onto which beds 17 and 18 are attached, against cross members 38 by means of wing nuts 39.

The curved surface, for instance urn-shaped container 40 (Figs. 4, 5, 10 and 11) onto which the composite impression obtained from impression plates 15 and 16 (Fig. 3) is transferred via transfer roller 25, is rotatably supported on bed plate 41 suitably secured to the framework of the machine. Bed plate 41 is preferably of sufficient

width so that a plurality of containers 40 can be mounted parallel to each other thereon. Thus the machine of my invention is by no means limited to the illustrative showing of the drawing of two containers 40 arranged in parallel. Suitable means for this rotatable support is shown in Figs. 16 and 17. It comprises plates 51 and 52 adjustably secured to block 53 (which in turn is secured to bed plate 41) by screws 54 passing through slots 55. These plates bear hinged to their outer ends plates 56 and 57 respectively, each bearing a pair of rolls 58, 59 and 60, 61 respectively, serving for the rotatable support of the curved surface to be printed, here shown as cylindrical container 37 provided with a protruding handle 42. Conventional means (not shown in the drawing) are provided to enable plates 56 and 57 to be locked in any desired position of inclination. Due to this manner of construction, curved surfaces of any dimensions within a wide range can be rotatably supported merely by changing the relative positions of plates 56 and 57. Furthermore, this manner of construction makes possible such a supporting of the curved surface to be printed that the part to be printed of said curved surface offers a maximum parallelism to shaft 32 of transfer roller 25 (see especially Figs. 4, 5, 10 and 11).

For transferring the impression carried by roller 25 onto the curved surface, for instance urn-shaped containers 40 (Figs. 4, 5, 10 and 11) roller 25 is brought, by means hereinafter to be described, into position above said curved surface 40 whereupon it is compelled into printing engagement therewith by means of arms 65, 66 (Figs. 1 to 5 and 9 to 12, incl.) bearing roller pairs 23 and 24, the center line between each pair of which lies in the same vertical plane as the center line of shaft 32 of roller 25. These arms act via these roller pairs on opposite ends respectively of the top of shaft 32 of said roller 25. The force exerted by these arms is sufficient to bring the surface of roller 25 into intimate contact with curved surface 40 to be printed. To assure such printing contact when non-cylindrical curved surfaces are printed, roller 25 preferably consists of a resiliently deformable material. In such case the force exerted by arms 65 and 66 on shaft 32 serves to resiliently deform said roller to such an extent that all parts to be printed of the non-cylindrical curved surface, 40, come into printing contact with the corresponding parts of the impression borne by roller 25, upon rotation of said roller.

Arms 65 and 66 are carried by rods 67 and 68 respectively. These rods (Figs. 4, 5, 10 and 11) slide in brackets 71, 72 and 73, 74 fastened to the inside of legs 2 and 3 respectively. To maintain arms 65 and 66 parallel to each other at all times the upper ends of rods 67, 68 are developed as rectangular bars, brackets 71 and 73 serving as guide surfaces to prevent rotation. Cross-member 75 is attached to the bottom ends of said rods 67 and 68, insuring that cross-arms 65 and 66 move together. For the reciprocation of rods 67 and 68 and of cross-arms 65 and 66 carried respectively thereby, plunger rod 94 of air cylinder 93 rigidly connected to cross-member 11 is bolted to the center of cross-member 75. Upon the admission of air under pressure into this cylinder, plunger rod 94 is forced downwards, carrying with it cross-piece 75 and rods 67 and 68 so that arms 65 and 66 are brought down onto shaft 32 of transfer roller 25, compelling the latter into printing

contact with curved surface 40. When said air is allowed to discharge from cylinder 93, springs 95 and 96, one end of which is connected to cylinder 93 and the other to cross-piece 75, serve to return plunger rod 94 into air cylinder 93, thus raising arms 65 and 66 and releasing shaft 32 of roller 25. The admission and discharge of air into and from cylinder 93 is effected by valve 76 actuated by foot pedal 77 (Figs. 1, 2, 3, 4, 5, 9, 10 and 11). Upon depression of foot pedal 77, main air line 99 coming from the compressed air source (not shown in the drawing) is placed in communication with line 98 and air under pressure is allowed to flow into cylinder 93 through Y-connections 97 and line 89. When foot pedal 77 is again in raised position the communication between line 98 and main air line 99 is broken and line 98 is placed in communication with the atmosphere, whereby the air in cylinder 93 is vented.

Various means may be employed for the positioning of transfer roller 25 above the curved surface 40 to be printed. In one embodiment, shown in Figs. 1 to 8 of the drawing, this means comprises parallel identical plates 46 and 47 (see especially Figs. 2, 7 and 8) secured to and extending above cross-members 5 and 8 respectively and each provided with opening 49 (Fig. 7) of sufficient size to receive shaft 32 of roller 25 and to secure it against any substantial lateral movement. When shaft 32 is seated in these openings (Figs. 2, 4 and 8) roller 25 lies directly above the curved surface 40 to be printed with which it is brought into printing contact by arms 65 and 66 as described above. In this position pinion 30 on shaft 32 engages spur wheel 62. Shaft 63 carrying the latter is journaled in bearing 64 (Figs. 1-5) which is supported by bracket 69 secured to leg 2 and cross-member 6. To pin 80 projecting from the face of spur wheel 62 there is connected in a freely rotatable manner one end of angle-shaped link 82, the other end of which is rigidly attached to the free end of rod 81 connected to the plunger (not shown in the drawing) which reciprocates in cylinder 83. The latter is pivotally carried in bracket 84 supported by plate 109 mounted on cross-member 7 (Figs. 1, 2, 4 and 5). Upon the admission of air under pressure into said cylinder 83, rod 81 is forced downward thus rotating spur wheel 62 and, via pinion 30, roller 25. When the air is permitted to discharge from cylinder 83 rod 81 is returned to its upper position by compression spring 85 surrounding same.

The relation between the number of teeth of wheel 62 and of pinion 30 and the stroke of rod 85 can of course be selected so as to impart any desired amount of rotation to roller 25 although this rotation will in general preferably be a maximum of 360°. With such relation determined, the amount of rotation of the roller can be decreased by a suitable stop, thus limiting the rotation of said roller 25 to an amount just sufficient to contact all the impression carried thereby with the curved surface 40. This, for instance, may be advisable where there is a protuberance on the curved surface, such as a handle or the like.

The admission of air into cylinder 83 is so controlled that it takes place only when cross-arms 65 and 66 have compelled roller 25, via shaft 32, into printing contact with curved surface 40 to be printed. In this position of the roller, pin 29 (Figs. 7 and 8), slidably mounted in bracket 45 secured to the inside of plate 46, is depressed against the action of spring 70 surrounding said

pin, one end of said spring being firmly connected to said pin and the other end resting against bracket 45. Upon the upward motion of arms 65 and 66, pin 29 is forced upward by spring 70, thus releasing pinion 30 from engagement with spur wheel 62.

The control of the air feed for cylinder 83 (Figs. 1-5 incl.) is effected by means of valve 92 carried by bracket 78 extending downward from cross-member 9. The means of actuation of this valve is as follows: Just before rod 94, and hence rods 67 and 68 reciprocated thereby, has traveled its maximum downward distance, shoulder 90 (Figs. 4 and 5), rigidly attached to rod 68, contacts handle 91 of valve 92, opening said valve and placing airline 87 in communication with line 88, which (pedal 77 being depressed) is filled with air under pressure, via Y-connection 93 and line 98, so that air can flow into cylinder 83, thereby rotating roller 25. When pedal 77 is again in raised position the air in cylinder 83 is vented to the atmosphere via 3-way valve 76 and as rods 67 and 68 move upwards under the action of springs 95 and 96, shoulder 90 ceases to press down on handle 91 which then, under spring action, returns upward closing valve 92 again.

Where it is desired to register the printing on the curved surface with respect to some point thereon, for instance a handle (such as 42 of curved surface 37 shown in Figs. 16 and 17) or an irregularity in the curve of such surface, or otherwise where the rotation imparted transfer roll 25 is less than 360°, it is necessary that roller 25 be so positioned in slot 48 of opening 49 of plates 46 and 47 (Fig. 7), before it is compelled into printing engagement by arms 65, 66 with the curved surface 40 to be printed (Figs. 1-5) and hence before it is rotated via spur wheel 62, that upon rotation thereby the entire impression carried by said roller 25 will be contacted with curved surface 40. For this purpose slots 48 (Fig. 7) are formed of a width less than the diameter of shaft 32 of roller 25 to cooperate with flats 100 and 101 (Fig. 6) to hold the shaft of said roller 25 against rotation and to determine that position in which the surface of said roller initially contacts curved surface 40 (Figs. 1-8). It is to be noted that this position will not coincide in general with the position of said roller 25 when in printing contact with curved surface 40 although such coincidence may take place where the curved surface to be printed is cylindrical. To further assist in registration the edges of plates 46 and 47 disposed towards impression plate 15 and 16 (Figs. 1, 2, 3 and 7) are sloped to provide a guide surface for flats 101 and 100 (Fig. 6) against which said flats may be slid into slots 48. The junction of these sloped guide surfaces of plates 46 and 47 with longitudinal cross-members 5 and 6 respectively is so positioned that when roller 25 is moved, via pinions 30 and 31, over racks 27 and 28 toward said plates, flats 100 and 101 come to rest against these guide surfaces (Figs. 1, 2, 3, 6 and 7). Thus when printing is terminated, roller 25 is removed from slots 48, and pinions 30 and 31 are returned into engagement with racks 27 and 28 by sliding flats 100 and 101 of roller shaft 32 down along said guide surfaces of plates 46 and 47. In this way it is assured that when roller 25 is again moved via racks 27 and 28 over impression plates 15 and 16 (Fig. 3), the impression received on said roller is exactly registered with the last impression.

Thus the method of operation of this embodiment of the machine of my invention is as fol-

lows: The objects defining the curved surfaces to be printed (40, Figs. 4 and 5) are placed on the rotatable supports defined by rollers 58, 59 and 60, 61 (Figs. 4, 5, 16 and 17). Roller 25 is moved, via racks 27 and 28, over ink impression plates 15 and 16 until flats 100 and 101 of shaft 32 of said roller come to rest against plates 46 and 47 respectively (Figs. 1-8). The roller is then further moved with these flats in contact with the forward guide surfaces of these plates and placed, via said flats, into slots 48, said roller thus coming to rest with its surface in contact with the curved surface to be printed (40). The operator then depresses foot pedal 77, arms 65 and 66 move down compelling roller 25 into printing contact with the curved surface, whereupon said roller is rotated via spur wheel 62 to an extent sufficient to bring all of the impression carried by said roller into printing contact with said curved surface. When the rotation forward has terminated, the operator releases foot pedal 77 whereupon spur wheel 62 returns roller 25 to its initial position, and arms 65 and 66 move upwards releasing roller 25. The operator then removes roller 25 from slot 48, returning it on to the table of the machine by sliding flats 100, 101 of shaft 32 down the guide surfaces of plate 46, 47 respectively until pinions 30 and 31 enter into engagement with racks 27 and 28 respectively. The roller is then moved back on said racks to the far end of the machine, the objects defining the printed curved surfaces (40, Figs. 4 and 5) are removed from rollers 58, 59 and 60, 61, new objects are inserted and the machine is now ready for the printing operation to be repeated. In the event that the object defining the curved surface to be printed bears a protuberance, for instance a handle (such as 42 of curved surface 37 shown in Figs. 16 and 17), an adjustable stop 50 (Figs. 16 and 17) may be provided on plate 51. Said stop is so positioned as to provide an abutment surface for handle 42 of container 37, thus delimiting the possible rotation of said container. The container is placed on the rotatable supports defined by rollers 58, 59 and 60, 61 in such a manner that handle 42 rests against the front side of stop 50. In this way an exact registration of the printing with respect to said handle 42 is assured.

In another embodiment of the machine of my invention, shown in Figs. 9-15 inclusive, the means for positioning transfer roller 25 above curved surface 40 to be printed comprises, similar to the first embodiment described above, parallel, identical plates 132, 133 (Fig. 15) secured to cross-members 5 and 6 respectively. The top of these plates, however, lies below the horizontal plane tangent to the bottom of shaft 32 of roller 25, so that said roller may, while traveling over racks 27 and 28 via pinions 30 and 31 respectively, pass over said plates until shaft 32 of said roller abuts against vertical extensions 136 and 137 carried by plates 132 and 133 respectively. Said plates (Fig. 15) bear roller pairs 138 and 139 respectively, which serve to rotatably support transfer roller 25 when the latter is compelled into printing contact with curved surface 40 by arms 65 and 66 acting on the ends of shaft 32 (Figs. 9-15). Said roller pairs 138 and 139 are so positioned that shaft 32 of transfer roller 25 does not contact them until said roller is compelled downward into printing contact with curved surface 40 by arms 65 and 66 (as described above). In order to avoid any interference by plates 132 and 133 with the seating of shaft 32 on the nip of said

roller pairs 138 and 139, said plates are provided respectively with recesses 136 and 137 (Fig. 15). Thus when shaft 32 moves downward under the action of arms 65 and 66 it slides against extensions 134 and 135 of plates 46 and 47 respectively to seat itself on roller pairs 138 and 139.

In this embodiment of my invention the means for the printing rotation of roller 25 comprises spaced racks 117, 118 and 119, 120 respectively mounted on slides 140, 141 and 142, 143 respectively (Figs. 9, 10, 11, 12, 13, 14). These racks are held apart by springs 124, 125, 126 surrounding pins 121, 122, 123 (Figs. 9, 10, 11, 13 and 14), the ends of which slide in bores 144 and 145, 146 and 147, 148 and 149 respectively, provided in slides 140, 141 and 142, 143 respectively. Said slides are held in vertical alignment by lateral plate 128 and by cross-member 5 and the downward extension thereof provided by plate 127 secured to cross-member 5 by plate 150 (Fig. 14). Plate 128 is secured to plate 127 by means of block 129 (Figs. 13 and 14). Shoulder 131 on plate 128 forms the surface over which slide 142 carrying rack 119 moves, while flange 130 of said plate 128 serves to limit the upward displacement of slide 140 carrying rack 117.

This double rack device is so arranged on each side of the machine that when flange 130 contacts slide 140 (the normal position), racks 117 and 118 form extensions of longitudinal racks 27 and 28 secured to cross-members 5 and 8 respectively, on which racks pinions 30 and 31 of transfer roller 25 travel (Figs. 3, 9 and 13). However, when roller 25 is clamped by arms 65 and 66 into printing contact with the curved surface 40 to be printed, and is thus forced downwards, racks 117 and 118 also descend to a corresponding extent due to the resilient mounting provided by springs 124, 125 and 126 (Figs. 11, 13 and 14). Upon release, i. e. upward motion, of arms 65 and 66 these springs serve to force roller 25 upwards and thus out of printing contact with curved surface 40, and similarly to force slides 140, 141 upwards against flange 130 of plate 128, and thus force racks 117 and 118 into alignment once more with longitudinal racks 27 and 28 respectively (Figs. 9, 10).

Plate 127 and block 129 are cut out to permit bottom racks 119 and 120 to engage with spur wheels 111 and 112 (Figs. 9, 12 and 13). Said spur wheels are arranged on each side of the machine, and are mounted on common axle 113, supported in bearings 114 and 115 respectively (Figs. 10 and 11). These bearings are mounted on brackets 151 and 152 respectively, secured to cross members 6 and 9 respectively. Spur wheels 111 and 112 are connected by eccentric rod 108 parallel to axle 113 (Figs. 9, 10, 11, 12). To the midpoint of rod 108 there is a pivotally connected rod 105 reciprocated by the plunger of air cylinder 102, which latter is supported in a pivotal manner in bracket 163, secured to the top of cross-beam 104 mounted on cross-members 7 and 10 (Fig. 11). Spring 106 surrounding rod 105 abuts against collar 107 carried thereby. The actuation of this plunger is identical to that described in the foregoing in connection with the first embodiment and the principles there set forth are of equal application here. Spur wheels 111 and 112 are thus rotated to a given extent, translating racks 119 and 120 and thereby racks 117 and 118 away from longitudinal racks 27 and 28. As during the rotation of spur wheels 111 and 112 roller 25 is clamped in printing contact with

curved surface 40, and as further translational movement of said roller is prevented, said roller is caused to rotate, due to the translation of said racks 117 and 118, to an extent sufficient to contact all of the impression carried by said roller 25 with curved surface 40.

The method of operating this second embodiment of the machine of my invention is exactly the same as in connection with the first embodiment, described above. The objects defining the curved surfaces to be printed (40, Figs. 10 and 11) are placed on the rotatable supports defined by rollers 58, 59 and 60, 61 (Figs. 10, 11, 16 and 17). If the object defining the curved surface to be printed is provided with a protuberance, such as handle 42 (on curved surface 37 in Figs. 16, and 17), adjustable stop 50 (Figs. 16 and 17) is first put in such position on plate 51 as to assure the desired registration of the handle with said stop, and the object defining the curved surface to be printed (37 in Figs. 16 and 17) is rotated on rollers 58, 59, 60 and 61 until handle 42 rests against the front face of stop 50. Roller 25 (Figs. 9-15) is moved over inked impression plates 15 and 16 (Fig. 3), via racks 27 and 28 (Figs. 3, 9 and 13), and then into contact with extensions 134 and 135 of plates 132 and 133 respectively (Figs. 9, 12, 13 and 15), via racks 117 and 118 forming extensions of racks 27 and 28 respectively. The operator then depresses foot pedal 77, arms 65, 66 move downwards and compel shaft 32 of roller 25 onto roller pairs 138 and 139 borne by plates 132 and 133 respectively (Figs. 9-15), thus bringing roller 25 into printing contact with the curved surfaces 40 to be printed. As racks 117 and 118 are resiliently supported by springs 124, 125, 126 they are likewise depressed due to the action of arms 65 and 66. Printing contact having been thus effected between transfer roller 25 and curved surfaces 40, spur wheels 111 and 112 commence their rotation (Figs. 10, 11, 12), whereby racks 117 and 118 move out, and roller 25 is rotated to an extent sufficient to contact all of the impression carried by said roller 25 with said curved surface 40. When the rack has terminated its outward motion, the operator releases foot pedal 77, whereupon racks 117 and 118 are returned to their initial position by the backward rotation of spur wheels 111 and 112 respectively, arms 65 and 66 move upwards releasing roller 25, and racks 117 and 118 return into alignment with longitudinal racks 27 and 28 respectively. The operator then moves roller 25 back over racks 117 and 27, and 118 and 28 via pinions 30 and 31 respectively to the far end of the machine, removes the objects defining the printed curved surfaces 40 from their holders, inserts new ones, and the machine is again ready for another printing operation.

In conclusion of this description of the machine of my invention it should be pointed out it is possible therewith to simultaneously print any number of curved surfaces, from one to a number limited solely by the dimensions of the machine. The fact that two objects defining curved surfaces are shown in the drawing (Figs. 4, 5, 10 and 11) as simultaneously being printed in no way limits the generic scope of my invention. Nor is the particular shape of the glass surfaces shown in the drawing (Figs. 4, 5, 10, 11, 16 and 17) intended to in any way restrict the breadth of my invention, it being again emphasized here that any shape of curved surface can be printed by the machine of my invention. Furthermore, as is obvious, the particular means shown by me for the

actuation of spur wheels 62 (Figs. 1-5), and 111 and 112 (Figs. 9-14) and of clamping arms 65 and 66 (Figs. 1-5, 9-12) is not limitative, electrical means, hydraulic means, mechanical means or known operating means of any kind being possible of use rather than the compressed air means shown and described by me herein.

The foregoing description is merely by way of illustration and not of limitation, it not being my intention that my invention be limited by anything save the following claims.

I claim:

1. In a machine for printing on an article bearing a curved surface, including a flat inked impression plate, means rotatably supporting such an article, a roller, an axle for said roller, at least one pinion on said axle, first means guiding said axle in a plane to bring said roller into rolling contact with and beyond said impression plate thereby imparting a transfer surface to said roller, at least one stop coactive with said first means guiding delimiting the end position of said axle in said plane, second means guiding said roller from said end position into printing contact with said such article, and means for turning said axle adapted to engage said pinion when said roller is in said printing contact, whereby said transfer surface is transferred to said such article.

2. In a machine according to claim 1 the improvement that a gear constitutes said means for turning.

3. In a machine according to claim 1, the improvement that a reciprocable rack constitutes said means for turning and the portion of said first means guiding adjacent said stop.

4. In a machine for printing on an article bearing a curved surface, including a flat inked impression plate, means rotatably supporting such an article, a roller, an axle for said roller, at least one pinion on said axle, first means guiding said axle in a plane to bring said roller into rolling contact with and beyond said impression plate, thereby imparting a transfer surface to said roller, at least one stop coactive with said first means guiding delimiting the end position of said axle in said plane, second means guiding said roller from said end position into printing contact with said such article and adapted to positively maintain contact between said transfer surface and said such article, and means turning said axle adapted to engage said pinion when said roller is in said printing contact, whereby said transfer surface is transferred to said such article.

5. In a machine according to claim 4 the improvement that a gear constitutes said means for turning.

6. In a machine according to claim 4, the im-

provement that a reciprocable rack constitutes said means for turning and the portion of said first means guiding adjacent said stop.

7. In a machine according to claim 6, the improvement that said rack is resiliently mounted for movement in the direction corresponding to the direction from said end position into printing contact.

8. In a machine for printing on an article bearing a curved surface, including a flat inked impression plate, means rotatably supporting such an article, a roller, a resiliently deformable covering on said roller, an axle for said roller, at least one pinion on said axle, first means guiding said axle in a plane to bring said deformable covering into rolling contact with and beyond said impression plate, thereby imparting a transfer surface to said covering, at least one stop coactive with said first means guiding delimiting the end position of said axle in said plane, second means guiding said roller from said end position into contact with said such article and maintaining sufficient force between said transfer surface and said such article to deform such deformable covering into intimate printing contact with said article, and means for turning said axle adapted to engage said pinion when said deformable covering is in said intimate printing contact, whereby said transfer surface is transferred to said such article.

9. In a machine according to claim 8 the improvement that a gear constitutes said means for turning.

10. In a machine according to claim 8, the improvement that a reciprocable rack constitutes said means for turning and the portion of said first means guiding adjacent said stop.

11. In a machine according to claim 8, the improvement that said rack is resiliently mounted for movement in the direction corresponding to the direction of application of said force onto said such article.

VINCENT J. TENETY.
